UNITED STATES PATENT OFFICE.

EDWARD FRANCIS FOLLIN, OF GREAT FALLS, MONTANA.

BOILER-WASHING NOZZLE.

Application filed March 23, 1922. Serial No. 545,966.

To all whom it may concern:

Be it known that I, EDWARD F. FOLLIN, a citizen of the United States, residing at Great Falls, in the county of Cascade and State of Montana, have invented certain new and useful Improvements in Boiler-Washing Nozzles, of which the following is a specification.

This invention relates to a nozzle through which to deliver a stream of water against the internal surfaces of a boiler, for instance, a locomotive boiler, and which is adapted to be manipulated to direct the stream in widely diverging directions and against widely distributed surfaces.

The object of the invention is to provide a tool of the kind stated which is of simple and durable construction and which will be highly efficient in service; also to construct a tool which will be readily introduced through the comparatively restricted opening afforded by the washout plugs of a locomotive boiler, and can be made to effect the wide distribution of its cleansing stream before mentioned by backward and forward movements in the direction of rotation about its axis, and such slight angular motion as the open washout plug will permit; also to provide such a tool with an improved arrangement of handles that facilitate the manipulations aforesaid.

In carrying out the invention, a water conducting tube is provided and equipped at its rear end with handles extending, respectively, in the direction of the axis of the tube and in a direction substantially transverse thereto; and this tube is made to extend beyond its handles a distance equal to the range of penetration required for reaching, say, to the center of the boiler space, and has its forward end closed against the escape of water in the direction of the axis of the tube, but provided with a jet opening or outlet nipple presented transversely to the axis and preferably in a direction opposite to the transverse handle so that by rotating the nozzle through the medium of its transverse handle, a range of delivery may be developed equal to a complete circle, and by varying the degree of intrusion of the delivery end into the boiler, every portion of every surface within reach from the washout plug can be made to receive the impingement of the cleansing stream. The handles are provided with

grips of heat non-conducting material, such, for instance, as sections of rubber, fiber, or other hose, and the axially presented handle is preferably developed by applying over the pipe end the hose that conveys the cleansing water to the nozzle.

Preferably, the nozzle will be provided with a valve in order that the operative may cut off the flow of water at will, and this valve may exist as a separate instrumentality or as a diametrically perforated plug intersecting the bore of the pipe and protruding beyond the same a distance suitable to provide the transverse handle through which the nozzle is to be manipulated.

In order that the invention may be fully understood, three embodiments thereof are illustrated in axial section in the accompanying drawings:

Figure 1 showing a form in which the controlling valve is omitted;

Figure 2 showing a form in which the controlling valve exists as a separate element in addition to the handles; and

Figure 3 showing a form in which the transverse handle and controlling valve are combined in a single structure.

Referring to all of the figures, 1 represents a tube of sufficiently small diameter to pass freely through the washout plug of a locomotive boiler and having a diameter which throughout the length of the nozzle is less than that of the standard washout plug openings of locomotives, thereby providing a free and non-obstructing external form of sufficiently length to adapt it to enter the relatively small washout plug opening of a locomotive and reach the desired distance within the boiler, say, to the center thereof. The front end 2 of the tube 1 is closed, and adjacent thereto the tube is flattened on one side, as at 3, and provided with a discharge port or nipple 4 which is accommodated by the flattened wall without protruding the nipple objectionably beyond the main transverse dimension of the nozzle.

Upon the tube, in rear of the portion that is required to enter the boiler, is a transverse handle 5 preferably provided with an insulating sleeve 6, for instance, a section of hose; and in substantially axial alignment with the tube 1 is a handle 7 also provided with heat insulation 8. Handle 7 is preferably in rear of handle 5, and by the use of these handles, any or all of the described move-

ments in the manipulation of the nozzle may be developed at will, the handle 5 serving especially as a means for developing rotation of the nozzle. The insulation 8 on the handle 7 is preferably the hose that brings to the nozzle the hot water commonly used for washing out boilers.

If desired, the nozzle 1 may be provided, as shown in Figure 2, with a controlling 10 valve 9 in order that the operative may control the delivery of water through the nozzle and avoid employment of an extra hand who is generally in attendance upon the valve at the drop of the washout line when 15 the washing operation is going on.

As suggested in Figure 3, instead of the valve 9 extending as a separate instrumentality, a plug valve 9^a may be combined with the shank 5 that serves as a transverse 20 handle, and a valve shell 10 can be introduced between pipe 1 and handle 7 in a manner to serve also as the means for applying the handle 5 to the nozzle. In Figures 1 and 2 the handle 5 is applied by welding it 25 to the side of the pipe 1.

I claim:

1. A boiler washing nozzle, comprising a tubular member adapted for intrusion

through the washout plug opening of a boiler and having a lateral discharge orifice 30 at its intruded end, and longitudinal and transverse handles on said nozzle in rear of the intruding portion thereof; said discharge orifice comprising a delivery nipple; and the intruded end of the nozzle having a 35 flattened wall in which said nipple is inserted; the overall dimensions of the intruded portion of the nozzle including the nipple being less than the diameter of such an 40 opening.

2. A washing nozzle constructed for intrusion through the washout plug opening of a boiler, and for angular, rotary, and longitudinal movement therein; said nozzle comprising a tube provided with manipulating 45 means at one end and having an intruding portion beyond such manipulating means which is of uniform diameter for substantially the whole length thereof, and is constructed at its end with a depressed side wall containing a transversely presented nipple terminating within said diameter.

Signed at Great Falls, Montana, this 7th day of March, 1922.

EDWARD FRANCIS FOLLIN.
